UNITED STATES PATENT OFFICE.

JAMES M. BROWN, OF PITTSBURGH, PENNSYLVANIA, ASSIGNOR TO WESTINGHOUSE ELECTRIC & MANUFACTURING COMPANY, A CORPORATION OF PENNSYLVANIA.

CONTROLLER.

1,421,160.

Specification of Letters Patent. Patented June 27, 1922.

Application filed November 18, 1917. Serial No. 202,842.

To all whom it may concern:

Be it known that I, JAMES M. BROWN, a citizen of the United States, and a resident of Pittsburgh, in the county of Allegheny and State of Pennsylvania, have invented a new and useful Improvement in Controllers, of which the following is a specification.

My invention relates to controllers and particularly to controllers for automatic 10 electrically-operated circuit interrupters.

One object of my invention is to provide a controller for a circuit interrupter that shall have means for preventing the interrupter from being held in its closed position 15 when an overload obtains thereon.

Another object of my invention is to provide an attachment for the controller of a circuit interrupter that shall be adapted to disconnect the movable member of the controller from its operating handle under pre- 20 determined conditions.

A further object of my invention is to provide a device of the above-indicated character that shall be inexpensive to construct, simple to connect and effective in 25 its operation.

In practicing my invention, I provide an attachment that is adapted to be inserted between the operating handle of the controller 30 and the movable drum of the same for the purpose of disconnecting the drum from the handle to permit the same to return to its inoperative or off position when an overload traverses the interrupter that is to be controlled. By the use of such a device, the 35 automatic features of the interrupter may function properly.

Figure 1 of the accompanying drawings is a side view, partially in elevation and partially in section, of a controller embodying 40 my invention; Fig. 2 is a view taken along the line II-II of Fig. 1; Fig. 3 is a view taken along the line III-III of Fig. 1, Fig. 4 is a diagrammatic view of an electrical 45 circuit embodying my invention; and Figs. 5, 6 and 7 are detail views of certain of the latching members.

An electrical circuit 1 is provided with an interrupter 2 having a closing electromagnet 50 3 and a tripping electromagnet 4. A hand-operated controller 5 is provided for controlling the circuit of the electromagnets 3 and 4 under normal conditions. A relay 6, that is operatively connected to a current 55 transformer 7, is adapted to effect the ener-

gization of the electromagnet 4 when an overload traverses the circuit 1, and an attachment 8 is provided for moving the controller to its off position when an overload traverses the circuit 1 to thus de-energize 60 the electromagnet 3 and permit the electromagnet 4 to trip the interrupter.

The controller 5 comprises a casing 9, stationary contact members 10, 10a and 10b and a rotatable drum member 11 upon which 65 movable contact members 12 are mounted. One end of a spring 13 is connected to the member 11 and the other end of the spring is connected to the casing 9. The spring 13 is adapted to normally hold the movable 70 member 11 in its off or inoperative position.

The attachment 8 comprises a casing 14, a sleeve or tubular member 15 that is operatively connected to a handle member 16, a sleeve or tubular member 17 that is connected through a pin 18 to the rotatable member 11. The sleeve 17 is disposed around the sleeve 15 and is provided with a segmental flange 19. A yoke member 20 is secured by screws 21 to the sleeve 15 and is 75 provided with a projection 22 that is adapted to engage one shoulder of the segmental flange 19. A pivotally mounted member 23 is mounted on the yoke 20 and has a projection 24 thereon for engaging the other shoulder of the segmental flange 19. A movable core member 25 is disposed in the sleeve 15 and is normally held in its outermost position by a spring 26. A winding 27 is disposed around the sleeve 15 for the purpose 80 of actuating the core member 25 when sufficient current traverses the circuit 1 to actuate the relay 6. A pin 28, mounted in the core member 25, extends through a slot in the sleeve 15 and into the hole 23a (Fig. 7) 85 of the pivotally-mounted member 23 for the purpose of actuating the same when the winding 27 is energized to thus so rock the member 23 as to cause its projection to disengage the shoulder of the flange 19.

If it is desired to manually operate close the interrupter 2, the handle 16 is turned, and, since the projections 22 and 24 engage the opposite faces of the segmental flange 19, any movement of the sleeve 15 will be transmitted through the sleeve 17 and the pin 18 to the movable member 11. When one of the contact members 12 engages the stationary contact members 10 and 10a, the electromagnet 3 will be energized from a source 29 of 110

electromotive force to thereby close the interrupter 2. If the handle be moved in the opposite direction, the contact members 10 and 10b are bridged to close the circuit 5 through the coil 4 and thus trip the interrupter 2. When the handle 16 is released, the spring 13 will cause the movable contact members 12 to return to off position, or to such position that, the winding of the actuating 10 electromagnet 3 will be de-energized.

If an overload traverses the circuit 1, after the handle 16 is moved to its closed position, the relay 6 will operate to energize the winding 27 and also the winding of the tripping 15 electromagnet 4. When the winding 27 is energized, the movable core member 25 actuates the pin 28 to cause the pivotally mounted member 23 to so move the projection 24 out of engagement with the edge of the 20 segmental flange 19 as to permit the spring 13 to turn the sleeve 17 and, consequently, the contact members 12 to their off positions or such position that the electromagnet 3 is de-energized. Thus, the handle 16 is entirely 25 disconnected from the controller 5 to preclude the operator from holding the interrupter in its closed position when an overload obtains on the same.

The attachment 8 may be applied to any 30 of the ordinary well-known types of hand-operated controllers and is not limited to the particular structure illustrated, as many modifications may be made therein without departing from the spirit and scope of the 35 invention as set forth in the appended claims.

I claim as my invention:

1. In a circuit-interrupting system, the combination with a circuit interrupter and 40 closing and tripping electromagnets therefor, of a controller for the electromagnets, and means for releasing the handle of the controller and for returning the controller to its off position when an overload obtains on 45 the interrupter.

2. In a circuit-interrupting system, the combination with an electrically-operated circuit interrupter, of a controller therefor, and means for releasing the handle of the controller and for returning the controller 50 to its off position when an overload obtains on the interrupter.

3. The combination with an electrically operated circuit interrupter, of a remotely disposed controller therefor, and means for 55 disconnecting the handle and for returning the controller to its off position to prevent the interrupter being held closed if an overload obtains thereon when the controller is actuated to close the interrupter. 60

4. The combination with an electrically operated circuit interrupter, and a controller therefor, of an attachment for the controller comprising means for disconnecting the handle from the controller and for returning 65 the controller to its off position when an overload traverses the interrupter at the time the controller is actuated to close the interrupter.

5. The combination with an electrically 70 operated circuit interrupter, and a manually actuated controller therefor, of a unitary attachment for the controller comprising means for returning the controller to its off position independently of its operating 75 handle when an overload traverses the interrupter as the controller is actuated to close the interrupter.

6. The combination with a controller for an electrically operated circuit interrupter, 80 of a unitary attachment therefor disposed between the actuated and actuating members of the controller for automatically disconnecting the same from each other when an overload traverses the circuit interrupter, 85 and means for returning the controller to its off position when it has been disconnected.

In testimony whereof, I have hereunto subscribed my name this 29th day of Oct. 1917.

JAMES M. BROWN.
